Inventor:
Axel Levedahl
By his own name
A. LEVEDAHL

UNITED STATES PATENT OFFICE

AXEL LEVEDAHL, OF AURORA, ILLINOIS, ASSIGNOR TO INDEPENDENT PNEUMATIC TOOL COMPANY, OF CHICAGO, ILLINOIS, A CORPORATION OF DELAWARE

ATTACHMENT FOR DRILLS

Application filed July 2, 1928. Serial No. 289,691.

This invention relates to a device for use with portable power driven drilling tools, such as pneumatic and electric drills, for drilling spotting holes for fastening screws for pieces of hardware and other fixtures.

The invention contemplates an attachment which when applied to a drill will automatically center the drill bit with respect to the screw-receiving opening in the fixture to be fastened in place and limit the depth to which the spotting hole may be drilled by the bit.

A further object of the invention is to provide the attachment with a guide which enters and fits within the screw-receiving opening so as to center the bit with respect thereto and enable the spotting hole to be drilled exactly in the center of said opening, so that the screw-head when brought into the same will be concentric and not eccentric therewith to spoil the appearance of the work.

A further object of the invention is to provide the attachment with telescopic parts and a stop therefor by which the depth of the spotting hole will be limited on one of the parts coming into contact with the stop.

The invention consists further in the matters hereinafter described and claimed.

In the accompanying drawings—

Fig. 1 shows an electric drill provided with the attachment of my invention; and

Fig. 2 is a vertical sectional view through the attachment to show its details of construction.

The portable power driven drilling tool in Fig. 1 is in the form of an electric drill, having secured together motor and gear case sections 1, 2 and a chuck 3 at the outer end of the gear case section and supporting a drill bit 4, as in tools of this general character.

The attachment of my invention comprises a collar 6 which is clamped about the forwardly extending tubular portion 5 of the gear case section 2 and which portion 5 is turned up concentric with the spindle of the tool. The collar 6 is slotted on one side and is drawn tightly about the portion 5 by means of a clamp screw. An apertured boss 7 is provided on the collar at one side thereof, and a post 8 has a pressed fit in said boss. The

post 8 has the length desired and extends forward from the boss in substantially parallel relation to the coinciding axes of the spindle and bit 4 of the tool.

A member 9, which may be in the form of a sleeve, has a sliding fit on the post 8 and is provided on one or both sides with an elongated slot 10, through which extends a pin or screw 11 carried by the post 8 to limit the sliding movement of the sleeve on the post. The upper or inner end of one or both of the slots 10 is closed so as to limit the outward movement of the sleeve 9 on the post and thus prevent the sleeve from sliding or dropping off of the post.

A coil spring 12 is located in the sleeve 9 and extends into a chamber or recess 13 which is provided in the outer end portion of the post 8, as shown in Fig. 2. The inner end of the spring engages the inner end of said recess and the outer end of the spring bears against the closed outer end of the sleeve 9 to normally force the sleeve outward on the post, as shown in Fig. 2. The outer end of the sleeve 9 is provided with a recess 14 to receive the adjacent end of the spring 12 so as to hold the latter central.

An arm 15 is provided at the outer end of the sleeve 9, and said arm extends over the center of the drill spindle. A tubular guide 16 is provided at the outer end of the arm 15 and extends forward therefrom concentric with the axis of the drill spindle. The guide 16 is provided with a passage or bore to receive the drill bit 4 and thus permit the latter to enter the work on forcing the drill toward the same, as usual in drilling operations. The guide 16 may have screw-threaded connection with the arm 15 for removability, and said threads may be left-handed ones so that the guide will not be turned off the arm in the right-hand rotation of the bit 4 during a drilling operation. The guide 16 is provided on one side with a slot 17 which opens into the bore of the guide to allow chips to freely pass out of the guide during a drilling operation.

The guide 16 is made of a size and shape to enter and fit within the screw-receiving openings 18 in a piece of hardware or other

fixture 19 which is to be fastened to the wood support 20 by one or more screws 21. These openings are usually of the countersunk variety, and the outer end of the guide 16 is 5 made angular or beveled to fit within the same, as shown in the drawings.

To drill the spotting holes for the screws 21 in the support 20, the piece of hardware 19 to be attached to the support is placed there- 10 on in the position it is to be fastened to the support by the screws 21. The operator holding the tool then inserts the guide 16 in one of the countersunk openings 18, and, with the outer end of the guide fitting within said 15 opening, the guide centers the drill bit 4 with respect thereto. Then by pressing the tool against the fixture 19, the drill bit 4 will be forced into the support 20 and drill the spotting hole therein directly in the center of the 20 opening in the rotation of the bit by the motor of the tool. Thus the fastening screw 21 may be driven into the support 20 exactly in the center of the opening 18 so that the head of the screw will properly fit in the opening and 25 come down flush with the outer surface of the plate 19, as desired for finished work. The spotting holes for the other screws may be drilled in the same way, and the screw-heads will all be concentric in their respective open- 30 ings 18 and not come down eccentric thereto to spoil the finish of the work as heretofore.

As the operator presses the tool against the work in drilling the spotting holes, the post 8 and sleeve 9 slide one with respect to the 35 other against the tension of the spring 12, and on the sleeve 9 contacting with the boss 7 further movement of the bit 4 into the work is stopped, thereby automatically limiting the depth of the spotting holes that may be 40 drilled by the bit.

On withdrawing the bit 4 from the support 20, the spring 12 forces the sleeve 9 outward until it is stopped by the pin 11 contacting with the inner end of the slot 10, in which 45 position the parts are normal and are set to center and gauge the next spotting hole to be drilled.

The attachment of my invention is simple in construction and operation and positive 50 and certain in action. By means of the de- vice, spotting holes for the screws may be accurately and quickly drilled to the depth desired and accurately formed in the center of the screw-receiving openings, without any 55 attention required on the part of the operator except to insert the guide 16 into the openings and press the tool against the work. The centering of the bit and gauging of the depth of its drilling are all automatic. The 60 attachment is useful when drilling spotting holes for screws for most all hardware fixtures, such as hinges and latches for the out- side of frames and doors for refrigerators, kitchen cabinets and the like; handles, 65 latches and the like on sliding windows with

frames of wood in passenger and sleeping cars, and other attachments in such cars, as corner pieces on seat backs, etc.

The details of structure shown and de- 70 scribed may be variously changed and modi- fied without departing from the spirit and scope of my invention.

I claim as my invention:

1. An attachment for portable power driv- 75 en drilling tools, comprising a collar to be clamped about the tool and having a boss at one side thereof, a post carried by said boss, a sleeve having a sliding fit on said post, a guide carried by said sleeve at its outer end and adapted to enter and fit within a 80 screw-receiving opening in a piece of hard- ware or other fixture on applying the tool thereto so that the spotting hole for the screw may be drilled by the bit of the tool central with respect to said opening, and a spring 85 for normally moving the sleeve outward on the post, said sleeve contacting with the boss to limit the depth of the hole that may be drilled by the bit.

2. An attachment for portable power 90 driven drilling tools, comprising a collar to be clamped about the tool and having a boss at one side thereof, a post carried by said boss, a sleeve slidably mounted on said post and having an elongated slot in one side 95 thereof, a pin carried by the post and extending through the slot, a spring in said sleeve for normally moving the sleeve outward on the post, an arm at the outer end of the sleeve and extending toward the bit of the 100 tool, and a guide carried by said arm at the bit and having a passage therethrough for the bit.

3. The combination with a portable power 105 driven drilling tool having a bit, of an at- tachment carried by the tool at one side of the bit and having slidably connected mem- bers, an arm carried by one of said members and extending toward the bit, an apertured 110 guide carried by the arm for the bit, said guide being in alignment with the bit and extending below the arm to enter and fit within a screw receiving opening in a piece of hardware or other fixture so that the spot- 115 ting hole for the screw may be drilled by the bit central with respect to said opening, and means associated with said members for holding the same against rotation and for limiting the depth of the hole that may be drilled by the bit.

In testimony whereof I affix my signature.
AXEL LEVEDAHL.
